US00D933323S

(12) **United States Design Patent** (10) **Patent No.:** **US D933,323 S**
(45) **Date of Patent:** ** *Oct. 12, 2021

(54) **GRILL SCRAPER**

(71) Applicant: **Thompson Brothers & Company, LLC**, Oakdale, MN (US)

(72) Inventors: **Jason S. Thompson**, Woodbury, MN (US); **Andrew N. Stadick**, Woodbury, MN (US); **Nathan A. Thompson**, North Saint Paul, MN (US)

(73) Assignee: **Thompson Brothers & Company LLC**, Oakdale, MN (US)

(*) Notice: This patent is subject to a terminal disclaimer.

(**) Term: **15 Years**

(21) Appl. No.: **29/723,101**

(22) Filed: **Feb. 4, 2020**

CLAIM

We claim the ornamental design for a grill scraper, as shown and described.

DESCRIPTION

FIG. 1 is a perspective view of our design for a grill scraper; FIG. 2 is a left side view thereof, the right side being identical thereof;

FIG. 3 is a top view thereof;

FIG. 4 is a bottom view thereof;

FIG. 5 is a back view thereof; and,

FIG. 6 is a front view thereof.

The broken lines in the drawings depict features of the grill scraper that form no part of the claimed design.
